UNITED STATES PATENT OFFICE.

PER AUGUST ROSELLE, OF RACINE, WISCONSIN.

WINDOW-SCREEN.

1,077,917.

Specification of Letters Patent.

Patented Nov. 4, 1913.

Application filed April 3, 1911. Serial No. 618,683.

To all whom it may concern:

Be it known that I, PER AUGUST ROSELLE, a citizen of the United States, residing at Racine, in the county of Racine and State 5 of Wisconsin, have invented certain new and useful Improvements in Window-Screens, of which the following is a specification.

This invention relates to improvements in window screen construction, and its object 10 is to produce a screen that is adjustable to several sizes of window. The complete screen is composed of four separable members, the two diagonally opposed parts being twins.

15 With the foregoing and other objects in view the invention consists in the combination and arrangement of parts to be herein-after fully described in the following specification, pointed out in the claims and illustrated in the accompanying drawings which form a part of said specification and in which—

Figure 1 is a front elevation of the screen complete. Fig. 2 is a horizontal section 25 taken on line 2—2 of Fig. 1. Fig. 3 is a section on line 3—3 of Fig. 1. Fig. 4 is an end view of the device. Fig. 5 is an enlarged section taken on line 5—5 of Fig. 1. Fig. 6 is a group view showing the four 20 component parts of the screen separated.

Like reference characters indicate corresponding parts throughout the several views.

This screen is composed of four screen 35 sections arranged in two pairs. The four parts are adapted to slide or to be partially telescoped one within the other and it is to this feature that the device owes its adjustability. When the four screen sections are 40 united the resulting figure is a quadrilateral, perhaps more nearly approaching an oblong than anything else but approaching a square shape as they are telescoped one within the other. The obliquely opposed 45 sections are twins making the complete screen a unit composed of two twin sections.

Referring to the drawings, A and A' form one screen section composed of two duplicate parts and B and B' form the other section. The outer edges of each one of the 50 four component parts of the complete screen which when the same is assembled will constitute the top and bottom and two sides of the screen are bounded by a piece or pieces 55 of flattened material of peculiar formation.

I will describe the formation of this outer

frame used on the parts A and B'. These parts telescope or slide upon each other, the part A lying upon or outside the part B' throughout their telescoped length, that is 60 looking upon Fig. 1 as a window seen from the inside, the relative positions of A and B' would be that just described. The formation of both is plainly shown in cross section in Fig. 2. First it will be seen the 65 material is bent at right angles to itself as at 1 and 2 which parts are the parts A and B' respectively in their telescoped position.

The flattened frame of A first forms an elongated U-shaped loop whose base is at 3, 70 whose outer flattened portion 4 extends beyond the top of this loop where it is bent at right angles to itself as at 1; the other side of this loop is the part 5 which lies in a plane parallel to 4 and which terminates at 75 a point short of the bend at 1 in the part 4. The part 4 is continued at right angles to itself from the point 1 and forms another elongated U-shaped loop whose base is 6 and one of whose sides is 7 which is the continuation of 4 from 1 to the base 6 and whose 80 opposite side 8 lies in a plane parallel to the plane of the continuation 7 and which is terminated at a point between the base 6 and the bend 1 in the side 7. It will be seen 85 that the entire flattened outer frame of A is composed of one piece of flattened material bent to form a pair of U-shaped loops disposed in planes at right angles to each other.

90 The formation of the part B' will now be described. Like part A this is also formed of a single piece of flattened material bent first to form an elongated U-shaped loop whose base is at 9 which surrounds the free 95 termination of the side 5 of the part A. One of the sides 10 of this loop lies upon one side of the portion 5 and the other side 11 of the loop lies upon the other side of the said portion 5. It will be seen that the side 10 extends to the base 3 of the first U-shaped loop of part A and the side 11 forms a side in common for the U-shaped loop just described and another U-shaped loop whose base is 12, disposed in an inverted position 100 with relation to the base of the last described loop, and whose other side 13 is pressed upon the side 11, leaving no space between the two sides, and extends the entire length of this side 11 when it branches away at 14 at 110 right angles thereto and forms a loop whose base is 15 and whose short side is 16 lying in

a plane parallel with the short side 8 of the outside loop whose base is 6 previously described. To hold the screen wire 18 in this flattened exterior frame a piece 17 is inserted in the last U-shaped loop described and the end thereof bent over and back upon the short side of this loop, the screen wire being placed between this last named piece 17 and the short side of the loop whose base 10 is 6.

17' is a piece shaped exactly like the piece 17 and inserted in the loop whose base is 15 in a manner similar to said piece 17 with the screen wire 18 placed as above described.

15 The intersection of parts B and A' is shown at the right in Fig. 2 and is simply the left hand part of this figure rotated 180 degrees on its vertical axis.

16 The relatively inner edges of the screen A are secured to vertically and horizontally disposed strips E and F respectively, the latter extending slightly beyond its point of contact with the former. The edges E', F' of A' correspond in every respect to E and F of A. The relatively inner edges of the screen B are secured to vertically and horizontally disposed strips E'' and F'' respectively, the latter extending slightly beyond its point of contact with the former. The edges E''', F''', correspond to E'', F'' of B.

17 On the inside horizontal edge of each of the sections A and A' a slightly curved prolongation of that edge as at X is formed as a bar to insects to prevent them from crawling 35 up between the overlapping screens. A similar vertical bar X' is provided on the inner vertical edges of the members B, B'; the two vertical insect bars are bent toward each other and the same is true of the horizontal 40 insect bars.

Y is a stop formed of a piece of metal secured upon the part 10 at a point covered by the part 4 when the sections are telescoped and bent back upon the said section 4 to prevent the total telescoping of the device by 45 sudden impact.

What I claim is:—

1. In a window screen, the combination with the frame which is composed of a piece of material shaped into a pair of elongated 50 U-shaped loops disposed in planes at right angles to each other and another piece of material shaped into three U-shaped loops, two of which are disposed in a plane at right angles to the third, of auxiliary pieces of 55 material adapted for partial insertion in two of the said U-shaped loops, part of each piece being bent back upon one side of each loop and a wire screen disposed between each of said pieces and its U-shaped loop. 60

2. In a window screen, the combination with the frame which is composed of a piece of material shaped into a pair of elongated U-shaped loops disposed in planes at right angles to each other and another piece of 65 material shaped into three U-shaped loops, two of which are disposed in a plane at right angles to the third, of auxiliary pieces of material obscurely disposed partly within two of said U-shaped loops and lapped over 70 upon one side of each of said loops and a wire screen disposed between each of said pieces and its U-shaped loop.

In testimony that I claim the foregoing as my own I have hereto affixed my signature 75 in the presence of two subscribing witnesses.

PER AUGUST ROSELLE.

Witnesses:
